UNITED STATES PATENT OFFICE.

JOHN J. ANDERSON, OF FRANKLIN, MINNESOTA.

BARREL-STAND.

1,288,794.

Specification of Letters Patent. Patented Dec. 24, 1918.

Application filed April 16, 1918. Serial No. 228,901.

To all whom it may concern:

Be it known that I, JOHN J. ANDERSON, a citizen of the United States, residing at Franklin, in the county of Renville and State of Minnesota, have invented a new and Improved Barrel-Stand, of which the following is a full, clear, and exact description.

An object of my invention is to provide a simple, inexpensive and convenient barrel stand by means of which a barrel can be easily balanced to facilitate the discharge of the contents of same.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a side elevation of the stand which is shown with a barrel carried or supported therein;

Fig. 2 is a top plan view of the barrel stand with the barrel supported by the stand;

Fig. 3 is a perspective view of the stand; Fig. 4 is a perspective view of the lever; and

Fig. 5 is a plan of the clamp.

Referring to the drawings, 6 are the horses, preferably shaped of angle iron, each braced near the open end by a member 7 and united at the ends by members 8. Each horse has a notch 9 in the top thereof, preferably toward one side, that is, off the central plane of the horses. These notches 40 form bearings for headed trunnions 10 extending outwardly from the lever 11 shaped into a U, the trunnions being near the open end of the U and constituting the fulcrums of the lever 11.

The extremities of the lever are depressed inwardly and have openings 12 into which enter trunnions 13 of a clamp 14. In consequence, the clamp 14 is pivotally mounted in the lever 11, which lever is, in turn, fulcrumed on the stand. The heads of the

trunnions 10 prevent the horses from spreading under the weight of the barrel 15 when the same is supported by the clamp 14.

To support a barrel on the stand the same is placed between the horses and connecting members 8. The clamp is then slipped over the barrel 15 and secured substantially midway between the ends. The lever is sprung on the trunnions 13 and the trunnions 10 moved into their bearings. The downward movement of the lever 11 will cause the barrel 15 to rise, as will be seen from Fig. 1. To retain the barrel in that position, a hook 16 is provided on the connecting member 8 nearest to the notches 9 to engage the lever 11 when the lever is near the connecting member 8. When the barrel 15 is supported as shown in Fig. 1 it may be tilted in any desired position on its pivot without much effort. It is self-evident that the U-shaped lever is long enough to allow the ends of the barrel to clear within the lever.

I claim:

1. A barrel stand comprising in combination, a pair of horses, means connecting said horses near the bottom, said horses having notches in the top, a U-shaped lever of the first class having headed trunnions adapted to engage the notches of the horses, the heads of said trunnions preventing said horses from spreading, and a clamp adapted to engage a barrel having trunnions bearing in the ends of said U-shaped lever. 75

2. A barrel stand comprising in combination, a pair of horses, means connecting said horses near the bottom to maintain said horses in a predetermined relation, each of said horses having a notch in the top, a U-shaped lever of the first class having headed trunnions between the ends adapted to engage the notches of the horses, the heads of said trunnions preventing said horses from separating at the top, and a clamp adapted to engage a barrel having trunnions, said U-shaped lever having the extremity of same disposed forwardly and openings in said depressed ends for engaging the trunnions of the clamp. 90 95

JOHN J. ANDERSON.
